The ornamental design for the fingernail enhancement, as shown.

DESCRIPTION

FIG. 1 is a perspective view of a fingernail enhancement showing my new design;

FIG. 2 is a top plan view of the fingernail enhancement in FIG. 1;

FIG. 3 is a side elevational view of the fingernail enhancement in FIG. 1;

FIG. 4 is a front elevational view of the fingernail enhancement in FIG. 1;

FIG. 5 is a bottom plan view of the fingernail enhancement in FIG. 1; and,

FIG. 6 is a cross-sectional view of the fingernail enhancement in FIG. 1 taken along line 6—6 shown in FIG. 2.

The broken line showing a fingernail on which a fingernail enhancement is mounted in several of the figures is for illustration only and does not form a part of the claimed design.
